Atty's.

UNITED STATES PATENT OFFICE.

AUGUSTO BUSCH, OF BASEL, SWITZERLAND, ASSIGNOR TO THE FIRM ELEKTRIZITALS-
WERKE LONZA, OF BASEL, SWITZERLAND.

BURNER FOR SOLID FUELS.

Application filed August 15, 1922. Serial No. 582,058.

To all whom it may concern:

Be it known that I, AUGUSTO BUSCH, a subject of the King of Italy, and resident of Basel, Switzerland, have invented new and useful Improvements in Burners for Solid Fuels, of which the following is a full, clear, and exact specification.

The object of this invention is a burner for solid fuels, especially metaldehyde. In the construction of such a burner, regard must be had to the special qualities of these new fuels, especially the de-polymerization of the metaldehyde under the effect of heat. This fact makes of first importance the complete utilization of the calorific value of the fuel under consideration for in earlier constructions of burner, a part of the products of de-polymerization was not burnt.

Furthermore as is well known, if the air admission is insufficient, all solid fuels burn with a more or less sooty flame. Compressed metaldehyde certainly shows this defect very little. If however, the boiler is placed close above the fuel and the flame beating upon the boiler takes a mushroom like shape, even metaldehyde forms a small quantity of soot. It would be possible to avoid this sooty formation by simply perforating the plate which supports the fuel and so providing for sufficient access of air. Such simple perforated plates have however two faults; in the first place in the case of fuel which produces gases on burning, as for instance metaldehyde does, a part of the gases escape downwards through the holes and spread out, and a part of the calorific value is lost. Further, there is a danger that pieces of fuel fall through and damage the table or the like on which the burner is standing.

Now it has been found that all these disadvantages can be avoided if there is provided beneath the perforated fuel support, a chamber with abundant access of air. To make the access of air as considerable as possible, large openings are made in the bottom and preferably also in the sides of the chamber. In some cases, the side walls of said chamber may be wholly omitted, there being nothing more than such wires or stays as are necessary to connect the bottom firmly with the top or fuel plate of the chamber; the burner then consists of two superposed perforated plates, the upper of which is the actual fuel support. In order that fuel may

not fall out of the chamber, the holes in the two plates are relatively staggered.

It is of advantage to form the plates with grooves or in any other way to make their surface uneven, so that there is as little surface of contact as possible between the fuel and its support; that is to say the air can reach the surface of the fuel from all sides at as many points as possible. This strengthens substantially the flame.

Such a burner exhibits a number of peculiarities and advantages which are summarized in the following. It should be noted that the burner can only be used for such fuels as do not melt during burning and are in part converted into gas.

The gas which passes downwards through the holes in the top of the chamber which serves as a fuel support, comes first into the chamber; since in this chamber there is a draught of air directly upwards the gas is driven into the flame space and there burns; it is therefore quantitatively consumed. But in part the gas burns in the chamber itself and so heats the fuel support and promotes the conversion of fuel into gas.

Pieces of fuel which fall through the holes in the top of the chamber are caught at the bottom of the chamber where they go on burning until consumed.

In most burners soot formation is dependent upon the amount and height of the layer of fuel and upon the distance between the fuel and the article to be heated. In the present burner there is no formation of soot at all; so without fear of making the article to be heated sooty, as much of the fuel can be put beneath it as there is room for; but the burner also does not produce soot even if there is very little fuel.

As a rule the shape of a flame depends upon the shape of the fuel so that, for instance, rods of fuel give a long flame. In the present burner, the flame takes the form and size of the burner so that a round flame is obtained even with long pieces of fuel if the burner is made round. That is a consequence of the even distribution of the gases formed from the fuel upon burning throughout the chamber.

The fuel support and chamber herein described can be mounted on any desired stand, for instance upon a folding stand and may be connected with it in various

ways, for instance in such a manner that its height can be adjusted.

It is obvious that this burner is not regulatable at will, but produces a flame the size of which depends upon the amount of the fuel and upon the size of the plate and of the holes in it. But the flame can be made regulatable if the burner is placed in a metal container or casing which is provided on its side or bottom with holes for the admission of air which are regulatable in size; for instance such a variation may be obtained by means of a perforated revolvable disc lying on the floor of the casing or of slides or the like; for instance in a burner of the size shown in the drawing 30 grammes of fuel are consumed in ten minutes if the holes in the bottom are fully open. By partly closing the holes the flame can be so diminished that the 30 grammes of fuel take about half an hour to burn. To increase the air draught a hood may be placed upon the case and will serve as a chimney.

25 In the accompanying drawing:

Figure 1 shows the improved burner in vertical section and

Figure 2 is a horizontal section thereof along the line 2—2 of Figure 1.

30 T_1 is the upper perforated plate which forms the support for the fuel M , T_2 is the lower plate of the burner, and the space between T_1 and T_2 is the aforesaid regulating chamber. In this chamber the small flames 35 Z play, heating the plate T_1 to promote the conversion of fuel into gas. F_1 indicates the shape of the main flame, if the described double plate burner is employed alone. If a regulatable flame is wanted, the double 40 plate burner supported by the central post S is surrounded by the casing U , to the bottom of which the post is fastened. The bottom of the casing U is provided with air admission apertures L_1 . Upon it is arranged a disc with apertures L_2 , which is 45 revolvable by means of the handle H and

more or less closes the holes L_1 . Any other suitable contrivance can be employed for this purpose. F_2 indicates the form of the main flame when such a surrounding casing 50 is used and when its bottom apertures are fully opened.

What I claim is:

1. A burner for solid fuel of metaldehyde, comprising a casing, air admission means 55 thereon, a support plate for the solid fuel within said casing, a lower plate arranged to define a secondary combustion chamber with said fuel support plate, an annular air passage round said chamber for admission 60 of air to the fuel on its support plate, large apertures in the latter for allowing fuel vapours to sink down into said chamber, large air admission apertures in the lower plate for the combustion of said fuel vapours 65 within said chamber, to allow of formation of invert heating flames, substantially as and for the purpose described.

2. A burner for solid fuel of metaldehyde, comprising a casing, air admission means 70 thereon, a support plate for the solid fuel within said casing; a lower plate arranged to define a secondary combustion chamber with said fuel support plate, an annular air passage around said chamber for admission 75 of air to the fuel on its support plate, large apertures in the latter for allowing fuel vapours to sink down into said chamber, large air admission apertures in the lower plate arranged in staggered position with 80 respect to those of the fuel support plate for the combustion of said fuel vapours within said chamber, to allow of formation of invert heating flames, substantially as 85 and for purpose described.

In witness whereof I have hereunto signed my name this 29th day of July 1922, in the presence of two subscribing witnesses.

AUGUSTO BUSCH.
